US00D933740S

(12) **United States Design Patent** (10) **Patent No.:** **US D933,740 S**
(45) **Date of Patent:** **** Oct. 19, 2021**

(54) **BARRIER**

(71) Applicant: **Elutions LLC**, Mobile, AL (US)

(72) Inventor: **Nemindra Mahathalagalage**, Mobile, AL (US)

(**) Term: **15 Years**

(21) Appl. No.: **29/652,607**

(22) Filed: **Sep. 30, 2020**

(51) **LOC (13) Cl.** **16-06**

(52) **U.S. Cl.**

(57) **CLAIM**

The ornamental design for a barrier, as shown and described.

DESCRIPTION

FIG. 1 is a top perspective view of a barrier showing the new design;

FIG. 2 is a bottom perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left elevation view thereof; and,

FIG. 8 is a right elevation view thereof.

The broken lines shown in FIGS. 2 and 4 are included for the purpose of illustrating unclaimed portions of the barrier and from no part of the claimed design.

1 Claim, 6 Drawing Sheets
